UNITED STATES PATENT OFFICE.

HENRY AIKEN, OF HOMESTEAD, PENNSYLVANIA.

CRANE.

SPECIFICATION forming part of Letters Patent No. 439,264, dated October 28, 1890.

Application filed March 26, 1889. Serial No. 304,881. (No model.)

To all whom it may concern:

Be it known that I, HENRY AIKEN, of Homestead, in the county of Allegheny and State of Pennsylvania, have invented a new and useful Improvement in Cranes, of which the following is a full, clear, and exact description, reference being had to the accompanying drawings, forming part of this specification, in which—

- 10 Figure 1 is a side elevation of one of my improved cranes, showing the cylinder and ram in vertical central section. Fig. 2 is an enlarged vertical section of the foot of the cylinder, ram, and base-plate. Fig. 3 is a plan view of the base-plate. Fig. 4 is a horizontal cross-section on the line IVIV of Fig. 2, showing the lower portion or foot of the crane-mast, the cylinder and ram being omitted for clearness of illustration.
- 20 In the accompanying drawings, 2 represents the cylinder of the crane, and 3 is the ram or plunger, which is preferably arranged within the cylinder, and is connected with the jib 4 in the manner set forth in my patent, No. 343,417, dated June 8, 1886, the ram being movable vertically by the water-pressure and being rotatory within the cylinder, and the jib being supported by the ram, so that all vertical strains to which the crane is subject shall be taken up by the water-cushion. Such construction is illustrated in the drawings, but, although very desirable, does not, unless so expressly stated in the claims, form a feature of limitation of my present invention, which is applicable to other constructions of cylinder and ram, and relates to the manner of connecting the cylinder with the water-connections and to the mode of stepping the mast at the base, the object of the invention being to simplify and cheapen the construction of the parts, to render them easy to put together or to separate, to render the mast of the crane easy to turn on its bearings, and with very simple means to make secure the fluid-connections, so that they shall not be apt to leak under the great pressure to which in the use of the crane they may be put.

The cylinder is stepped at the lower end in a base-plate 5, consisting of a strong casting, which is firmly secured by bolts or otherwise to a suitable foundation. A water-passage 6 extends through the flange of the base-plate

and terminates in the center of the bottom of the cylinder cavity or socket. The foot of the cylinder is made of considerably less diameter than that portion thereof which contains the ram, and the axial bore or water-way 7 formed therein is adapted to register with the end of the water-way 6 in the base-plate. At the extreme lower end of the foot 60 8 is a circular tongue 9, concentric with the axis of the foot, and a correspondingly-shaped groove is formed in the base-plate in such position as to receive the tongue when the cylinder-foot is stepped. A gasket 10 of rubber 65 is placed in this groove beneath the tongue 9, and the groove is made sufficiently shallow that when the cylinder-foot is stepped in the base-plate the entire weight of the cylinder shall be exerted upon the narrow bearing of 70 70 the tongue on the gasket. The weight of the cylinder upon the gasket is the only means necessary to be employed to make tight the water-connection between the base-plate and the cylinder. Its action in this regard is perfect, and as the pressure on the gasket and the consequent security of the joint increase with the weight or burden of the crane the joint is tight under all conditions. When set in position in the base-plate, the cylinder is held 75 firmly and is rendered non-rotatory by means of a key b, which extends through the base-plate, as shown in Figs. 2 and 3. Somewhat above the tongue 9 the base-plate is formed with a seat 11, on which the foot of the mast 85 rests and turns. The mast-foot consists of a sleeve 12, which fits neatly around the contracted foot 8 of the cylinder, and is therefore itself of small diameter, and is provided with a wider portion or flange 13, preferably cast 90 integral therewith, which extends for a short distance up around the wider portion of the cylinder.

The I-beams 14, forming the rotatory mast of the crane, are arranged on opposite sides 95 of the cylinder, and are bolted at their lower ends to the flange 13, as shown in Fig. 4. They are arranged in substantially the same way and perform substantially the same functions as do the corresponding parts shown in my 100 patent, No. 343,417, above cited, and at their upper ends are secured to a block 15, whose journal 16 fits within suitable bearings 17.

In the use of the crane the vertical strain

- of the jib falls upon the ram 3, on which it is mounted; but as the jib is moved horizontally on the axis of the ram the mast formed by the I-beams 14 also turns on the bearing-surface 5. face 11 at its foot. The small diameter of this bearing, by increasing the proportion of the radius of the sweep of the jib to the radius of the bearing, renders the crane much easier to turn on its vertical axis than where such bearing is larger, as in my said patent, and is thus a means of saving labor in the use of the crane.

In order to prevent dangerous consequences which might ensue if the foot of the cylinder should break, I prefer to construct the base-plate 5 with a curtain or guard 18, which is preferably (though not necessarily) cast integrally with the base-plate and extends upwardly for a short distance around the contracted foot of the mast and above the top of the lateral bearing of the cylinder-foot in the base-plate 5. If the foot of the cylinder should break, this guard would still confine the mast and would keep it and the cylinder in an upright position.

My invention is susceptible of many modifications in form and relative arrangements of the parts, without involving a departure from the principles thereof, as expressed in the following claims, each of which states an item of invention independent of and unlimited by the elements and limitations contained in other claims.

The advantages of my invention will be appreciated by those skilled in the art.

The crane is very simple in its structure, is easily fitted together, and because there are no difficult water-connections to couple or uncouple (as when the water-pipe enters the cylinder laterally) the cylinder if injured by freezing or otherwise may with little difficulty be removed and a new cylinder substituted therefor, all that is necessary being to support the jib, to remove the key b, to lift the cylinder from the base-plate, and to replace it with another cylinder, which is in turn held by the key. Other advantages of the invention have been stated in the course of the foregoing description.

50. I claim—

1. The combination of the base-plate or

socket having a water-passage and the upright stationary cylinder bearing on the base-plate and closing the joint by pressure thereon, said cylinder having in its end a passage registering with the said water-passage, substantially as and for the purposes described. 55

2. In a crane, the combination of a stationary cylinder having a contracted foot, a rotary mast having a contracted foot fitting around the foot of the cylinder, and a step for the mast, substantially as and for the purposes described.

3. In a crane having a contracted foot, such as the foot 8, forming a journal on which the crane is rotatory, the combination, with such foot, of a base-plate or socket in which it is stepped, and in which it has a lateral bearing, and an external curtain or guard which extends above the top of said lateral bearing, substantially as and for the purposes described.

4. In a crane, the combination of the base-plate or socket having a water-passage, an upright stationary cylinder having a hollow end stepped in said base-plate or socket and connected therewith by a tongue-and-groove joint, and a gasket on which the cylinder end rests, substantially as and for the purposes described. 75

5. The combination of the base-plate or socket having a water-passage, the upright cylinder having in its end a passage registering with the water-passage in the base-plate, and a key connecting the cylinder and base-plate, substantially as and for the purposes described. 80

6. In a crane, the combination of the stationary cylinder, a base-plate or socket on which it is stepped, said base-plate or socket having an external curtain or guard extending above the bearing of said cylinder in the base-plate or socket, and a rotary mast encircling the cylinder at the base, and having a flange 13, encircling the cylinder, substantially as and for the purposes described. 95

In testimony whereof I have hereunto set my hand this 23d day of March, A. D. 1889.

HENRY AIKEN.
